UNITED STATES PATENT OFFICE.

RICHARD CLIPSTON STURGIS, OF BOSTON, MASSACHUSETTS.

DESIGN FOR A FIRE FAN.

Application filed April 5, 1922. Serial No. 1,548. Term of patent 14 years.

To all whom it may concern:

Be it known that I, RICHARD CLIPSTON STURGIS, a citizen of the United States, and resident of Boston, county of Suffolk, State of Massachusetts, have invented a new, original, and ornamental Design for Fire Fans, of which the following description, in connection with the accompanying drawings, is a specification, like characters on the drawings representing like parts.

The figure shows a fire fan.

I claim:

The ornamental design for a fire fan, as shown.

In testimony whereof, I have signed my name to this specification.

RICHARD CLIPSTON STURGIS.
